US00D936861S

(12) **United States Design Patent** (10) **Patent No.:** **US D936,861 S**
(45) **Date of Patent:** **** Nov. 23, 2021**

(54) **CONNECTOR FOR A MODULAR STRUCTURE**

(71) Applicant: **2724889 ONTARIO INC.**, Oakville (CA)

(72) Inventors: **Jacek Styrc**, Oakville (CA); **Sebastian Lysiak**, Bielsko-Biala (PL)

(73) Assignee: **2724889 ONTARIO INC.**, Oakville (CA)

(**) Term: **15 Years**

(21) Appl. No.: **29/746,174**

(22) Filed: **Aug. 12, 2020**

(51) LOC (13) Cl. **25-01**

(52) U.S. Cl.

USPC **D25/133**

(57) **CLAIM**

The ornamental design for a connector for a modular structure, substantially as shown and described.

DESCRIPTION

FIG. 1 is a front perspective view of the connector for a modular structure;

FIG. 2 is a plan view of the connector for a modular structure of FIG. 1;

FIG. 3 is a bottom view of the connector for a modular structure of FIG. 1;

FIG. 4 is a front view of the connector for a modular structure of FIG. 1;

FIG. 5 is a back view of the connector for a modular structure of FIG. 1;

FIG. 6 is a side elevation of the connector for a modular structure of FIG. 1;

FIG. 7 is a side elevation from the opposite side to FIG. 6 of the connector for a modular structure of FIG. 1; and, FIG. 8 is a rear perspective of the connector for a modular structure of FIG. 1.

1 Claim, 8 Drawing Sheets
